TYPEWRITING MACHINE

Henry L. Pitman, Hartford, Conn., assignor to
Underwood Elliott Fisher Company, New York,
N. Y., a corporation of Delaware

Application November 5, 1938, Serial No. 239,045

14 Claims. (Cl. 197—66)

This invention relates to typewriting machines, and more particularly to devices whereby the typing carriage upon reaching a line-end position is automatically caused to be returned to a line-start position. Such machine is generally exemplified in Patent No. 1,238,908 to F. A. Hart, dated September 4, 1917, and Patent No. 1,679,741 to H. L. Pitman, dated August 7, 1928.

In certain kinds of work it is required to change frequently, from a normal line-end position of the carriage to a different line-end position. The typing of telephone toll bills is an example of such work. The toll bill lists a subscriber's calls for a given period and the data for each call is typed on its individual line of the bill. The data for an ordinary call may consist of the place called and the toll charge. Thus, ordinary calls may be typed within uniform line lengths covering merely a place-called column and a toll charge column of the bill. As the final character is typed for the entry in the last of these columns in a line for an ordinary call, the carriage takes a final step to what may be called the ordinary line-end position and the carriage thereby engages and actuates a carriage return starter or other suitable device to cause automatically the carriage to be returned to line-start position.

Other calls are notated with additional data such as a tax upon a toll charge exceeding a specified amount, and a code symbol. The bill form, therefore, includes, after the previously mentioned columns, a tax column and a code column.

It will be understood now that preparatory to extending the typing of a call line on the bill into the tax and code columns, the automatic start of the return of the carriage from the ordinary line-end position must be prevented.

The object of the invention is to provide simple, efficient, time and labor saving means for preventing, in respect of typing extended lines, the automatic start of returning the carriage from the ordinary line-end position.

The invention may include the following advantageous features. A particular key operation may be instituted by the typist from the vicinity of the typewriter keyboard preparatory to the carriage reaching the end of an ordinary line and such key operation may determine that the carriage will not automatically be caused to be returned from the end of that line so that the line may be extended. Further, such key operation may determine that the carriage will automatically be caused to be returned at the

end of typing the extended line. Still further, concomitantly with the return movement of the carriage, it may be determined automatically that thereafter, that is, until the key operation is again effected, the carriage will automatically be caused to be returned from the ordinary line-end position.

The foregoing and other objects, features and advantages will be apparent from the following description of a preferred embodiment of the invention, illustrated in the accompanying drawings in which:

Figure 1 represents a telephone toll bill.

Figure 2 is a cross sectional side view of a typewriter employing the invention.

Figure 3 is a perspective of the mechanism for controlling the start of the carriage return.

Figure 4 is a perspective of means for guiding the toll bill around the platen.

Figure 5 is a front elevation showing the means, for controlling the start of the carriage return, in normal positions.

Figure 6 is a front elevation of the Figure 5 means showing the latter conditioned for controlling the carriage return start in respect of an extended line of typing.

Figure 7 is a perspective showing details of the mechanism.

Transverse rows or banks of type keys 10, Figure 2, of the usual keyboard 11 are mounted on key levers 12 having operative connections, not shown, to type bars 13 fulcrumed at 14. By means of said keys, said type bars are swingable upwardly and rearwardly to print against a toll bill sheet 15 feedable around a platen 16. The platen is mounted in a carriage 17 that includes a frame having a front bar 18 having roller engagement at 19 with a front track 20, the carriage frame also having lugs 21 engaging a rear track 22. The tracks 20, 22 are supported by side frame-members 23 of the machine framework.

A spring motor 24, escapement mechanism 25, and a carriage feed rack 26 cooperate to feed said carriage 17, and its platen 16, in letter feed direction at operations of the type bars 13 or the usual space key 27.

The front bar 18 of the carriage has a tappet 30 to engage and depress a cam lever 31 when the carriage, in its advance, reaches a predetermined line-end position, the depression of said cam lever in turn rocking a transverse bar 32 downwardly, said bar 32 having side arms 33 fulcrumed loosely upon a rock shaft 34 journaled in the frame side-members 23. A spring 28,

Figure 6, normally upholds the bar 32 against a stop 29, Figure 3. Said bar 32 has an ear 35 connected by a link 36 to a lever 37 turnable about a pivot stud 38 on the framework. Said lever 37 has a lateral tab 39 for lifting a trip link 40 out of latching connection with a key-lever comb plate 41. Said trip link 40 is pivotally connected at 43 to an arm 44 of a rock shaft 45 having suitable bearings, not shown, presented by the framework. Said rock shaft 45 is connected by arm 46, link 47, and arm 48 to a rock shaft 49 also suitably journaled in the framework. Said rock shaft 49 presents an arm 50 for engaging and shifting a carriage return pinion 51 along a shaft 52, suitably journaled in the framework, to clutch or unclutch said pinion with a clutch collar 53 on said shaft 52. Said shaft 52 has a reduction gear connection 54 to a shaft 55 extending from an electric motor 56 mounted upon the rear of the typewriter frame.

The rock shaft 45 has an arm 57 to which is pivoted a pusher 58 extending rearwardly to control a switch 59 for starting and stopping said motor.

When the carriage tappet 30, at a line-end position of the carriage, depresses the cam lever 31, the transverse bar 32 and link 36 are correspondingly depressed, thereby rocking the lever 37 counter-clockwise of Figure 2 to lift and release the trip-link 40 from interlock with the comb plate 41. It results that a spring 60 moves said trip link rearwardly, thereby rocking the shaft 45 counter-clockwise and the shaft 49 clockwise to shift the carriage return pinion 51 into clutch with the drive shaft collar 53. The counter-clockwise rotation of the shaft 45 also acts through the pusher 58 to cause the switch 59 to close to start the motor 56. The resulting rotation of the pinion 51 moves the carriage rightwardly or in return direction, as viewed from the front of the machine, said pinion meshing with a rack 61 on the carriage.

When the carriage in its power driven return movement reaches a predetermined point, the carriage tappet 30 encounters and depresses a dog 62 that is keyed to the cross shaft 34 thereby by rocking said shaft 34 clockwise of Figures 2 and 3, to turn the shafts 45, 49 to shift the carriage return pinion 51 forwardly to unclutch it from the drive shaft collar 53. The carriage-tappet-rocked shaft 34 has an arm 64 connected by a link 65 to an arm 66 of the rock shaft 45. The rotation of the shaft 45 that results in unclutching the pinion 51 from the drive shaft collar 53 also restores the trip-link 40 to latched position and also draws the pusher 58 forward to cause the switch 59 to open to stop the motor.

The trip-link 40 may also be released, to start a carriage return, by means of a manually operable carriage return key lever 67 pivoted at 68 to the framework, it being obvious that as said key is rocked counter-clockwise of Figure 2, it engages a by-pass pawl 69 on the forward end of the trip-link 40 and thereby lifts and releases said link 40 from the comb plate 41.

A carriage-return-limiting margin-stop body 71, Figure 3, has a stop lug 72 that cooperates with a counter stop 73 on the carriage for finally arresting the carriage return movement after the carriage tappet 30 has served to depress the dog 62 to disconnect the carriage from the motor. Said body 71 is supported partly on the rock shaft 34, without binding the latter, and partly on a cross rod 74 supported by the frame side-members 23 and held endwise as by collars 75,

10 Figure 3. Ordinarily, the margin stop 71, 72, along with the dog 62, is adjustable laterally to different stations and is located at any station by means of a pawl 76, and teeth 77 on said cross-rod 74.

The mechanisms thus far described operate substantially as set forth in the aforesaid Pitman Patent No. 1,679,741 and Hart Patent No. 1,238,908, to which reference may be had for other details.

15 A work web 79 affords a succession of telephone-toll-bill forms 15 of the kind seen at Figure 1. Each form includes a "Place called" column, an "Amt." or toll-charge column, a "Tax" column and a "Code" column. The work web 79 may be located transversely of the carriage and platen and may be guided around the latter by means of a work web chute 80, Figure 4, of the kind described in Patent No. 1,160,459, to J. A. B. Smith, dated November 16, 1915.

The first three typed lines "a" on the toll bill, Figure 1, exemplify ordinary calls, that is, calls for which the toll amount is less than 50¢. For such ordinary call, no entry is typed in the "Tax" or "Code" columns of the bill and hence the cam lever 31 may be placed so that as the carriage takes the letter-feed step following the typing of the last digit of the amount, the carriage tappet 30 depresses said cam lever and thereby, as hereinbefore explained, automatically initiates or causes a return of the carriage by means of the motor mechanism.

20 The return limiting margin stop 71, 72, along with the dog 62, may be placed to terminate said return so that the carriage is left or settles at the letter space position corresponding to the place where the first character is to be typed in the "Place-called" column of the bill. If desired, the margin stop 71, 72 and dog 62 may be secured against lateral displacement from their determined position by collars 82 secured to the shaft 34 by set screws 83. The dog 62 and the rock shaft 34 may have a spline connection 84 so that the dog may rock said shaft 34 and yet be shiftable along the latter.

25 The toll amount for a call may be 50¢ or more and in that case a tax charge is imposed and is to be listed on the bill in the "Tax" column and a code symbol may also be listed in the "Code" column. The typing of the line on the bill for such call, therefore, extends into the "Tax" and "Code" columns of the bill as exemplified by the lines "b", Figure 1. Therefore, in typing an extended or tax and code including line "b", the 30 automatic causing of a return of the carriage from the line-end position determined for the ordinary call line "a" must be prevented and for this purpose the following mechanism may be provided.

35 The cam lever 31 is pivoted upon a headed stud 86 in an arm or wall 87 extending leftwardly from a body block 88 supported by but not binding the rock shaft 34. A U-shaped clip 89 is suitably and rigidly fastened, as by riveting 90, Figure 2, to the back of the wall 87 and embraces the cross rod 74 to keep said block 88 from turning about said shaft 34.

40 A transverse bar 91 is fulcrumed at one end on a fixed stud 92 spaced to the left of the body block 88 and extends rightwardly beyond the latter to a pivotal connection 93 with a link 94 that extends downwardly to a pivotal connection 95 with an ear 96 on a key lever 97. Said key lever 97 may be fulcrumed at 90, like the type key levers 12, and extends forwardly

through guide slot 100 in the comb plate 41 to present a key 98 at the typewriter keyboard 11. A spring 99 tends to keep the key lever 97 and hence the link 94 and bar 91 in normal positions wherein the key lever stops against the upper end of said slot 100. In the normal position of the bar 91, a shoulder 101 thereof engages the left end of a cleat 103 suitably fastened, as by rivets, not shown, to the under side of the block 88. The cleat 103 presents an ear 104 to which is attached a spring 105 tensioned to urge the unit comprising 31, 88, 89, 103 leftwardly, said unit therefore tending to shift leftwardly.

The fulcrum stud 92 for the shouldered bar 91 may be in a block 106 supported on but not binding the rock shaft 34. At its part 107, the block 106 may be supported by the cross rod 74 and may be fixed to the latter by set screws 108. The block 106 also presents an anchor 109 for the spring 105.

With the key lever 97 and bar 91 in normal positions, Figures 3 and 5, the spring 105 keeps the block 88 in normal position with its cleat 103 against the shoulder 101 of the bar 91, and the latter prevents leftward shift of the block 88. Thus, the cam lever 31 is located laterally in a normal position, Figure 5, wherein it will be engaged and depressed by the carriage tappet 30 to depress the transverse bar 32 and so cause automatically a power return of the carriage to line-start position when the carriage takes the letter feed step following the typing of the last digit in the "Amt." column of the bill 15.

If the amount is say fifty cents or more and therefore subject to a tax, the typist may, preparatory to extending the typing of a line into the "Tax" and "Code" columns, prevent automatic causing of the return of the carriage from the "Amt." column by depressing the key lever 97 by means of its key, at any time before typing the last digit in the "Amt." column. The key 98 may be distinguished from the other keyboard keys 10 by the character "Tax." The bar 91 is, of course, depressed about its fulcrum 92 by depression of the key lever 97, and its shoulder 101 is thereby depressed below the cleat 103 of the block 88. It results immediately that the block 88, and its cam lever 31, are shifted leftwardly, along the rods 34, 74, by the force of the spring 105 and the leftward shift may be stopped by a secondary shoulder 110 of the depressed bar 91, as in Figure 6.

In this leftwardly shifted position, the cam lever 31 is stationed for coacting with the carriage tappet 30 to cause automatically a return of the carriage at the time when the carriage takes the letter feeding step following the typing of the last character in the "Code" column of the bill, said last character representing the end of the extended line. For placing the secondary shoulder 110 level with the cleat 103, the down-stroke of the key lever 97, and hence of the bar 91, may be limited by a suitable key lever stop 111 on the comb plate 41.

It will be obvious that upon loosening the set screws 108, the block 106, together with the shouldered bar 91, may be adjusted laterally. Such adjustability facilitates determining exactly the positioning of the shoulders 101, 110 relatively to the letter-space carriage positions or steps at 70 which carriage tappet 30 is to actuate the cam lever 31 for starting a carriage return from a normal-line-end or an extended-line-end. As is conventional, link 94 is sufficiently loose at the pivot 95, and the connection is therefore sub- 75

stantially flexible, to permit said link 94 to swing laterally about said pivot so that its upper end at the pivot 93 may move laterally to permit a material extent of lateral adjustment of shouldered bar 91.

The rightward or return movement of the carriage may serve automatically to restore or shift the unit 31, 88, 89, 103 back to normal position. Therefore, the clip 89 includes a lateral extension 113 to which is secured, by a screw and elongate slot adjustment device 114, a plate 115 adapted to be engaged by a pin 116 in the front bar 18 of the carriage. By means of the adjustment device 114, the plate 115 may be set so that said unit will have been restored or shifted rightwardly, by the pin 116, in the carriage return movement, to bring the left end of the cleat 103, say, $\frac{1}{2}$ of an inch to the right of the bar shoulder 101 when the carriage counter-stop 13 stops 20 against the stop lug 72. This permits the shouldered or latch bar 91 to rise under the force of the key lever spring 99 and its shoulder 101 to confront the cleat 103. It will be obvious that in the leftwardly shifted position of said unit, the bottom of the cleat 103 may abut a step 117 of the latch bar 91 to maintain the latter in depressed position.

It will be understood that after banking or stopping in its return movement against the stop lug 72, the carriage may have the usual drop back movement of about a letter space due to the usual back lash of the escapement 25. At the end of such drop back movement, the carriage will be settled at the letter space or line start position 35 corresponding to the first character space in the "Place called" column. By such drop back movement of the carriage, its pin 116 recedes from the plate 115 to permit the unit 31-103 to be released from the bar shoulder 101 by depression of the key lever 97.

The wall 87 of the unit 31-103 may have a lug 118 to coact with the tappet 30 for positively limiting leftward movement of the carriage at either position of said unit. The dog 62 may have 45 an anti-friction roller 119 for engagement with said tappet 30. The cam lever 31 may have a nose 120 for engaging the bar 32 and said cam lever may be stopped against upward displacement by a pin 121 in the wall 87. The bar 32 may be similar to the usual toothed bar employed at this location in Underwood machines.

It will be apparent, now, that for determining that the automatic start of the return of the carriage will not be effected from the ordinary line end, that is, from the "Amt." column, the typist merely depresses the key 98. Moreover, the depression of said key determines that return of the carriage will automatically be started from the end of the extended line, that is, from the "Code" column. The key is easily depressible since it is conveniently placed at the typewriter keyboard 11. Further, the condition for automatic start of the carriage return from the "Amt." column is automatically reestablished by the return movement of the carriage.

Variations may be resorted to within the scope of the invention and portions of the improvements may be used without others.

What is claimed is:

1. In a typing machine; a frame, an advanceable and returnable carriage thereon, an element on the frame, another element on the carriage to encounter and engage said first element during the carriage advance, power mechanism responsive to the engagement of said elements to cause

said carriage to be returned, means tending to effect a relative shift of said elements in the direction, substantially, of carriage movement, means normally effective to prevent said shift, and means operable at will to disable said preventing means and thereby cause said shift, whereby said carriage is returnable by said power mechanism upon reaching different positions in its advance, one position being determined when said preventing means is effective and another position being determined when said preventing means is disabled.

2. In a typing machine having a frame, a carriage thereon, and a carriage returning mechanism; an element shiftable on the frame in the direction, substantially, of carriage movement, said element being engageable by the carriage to cause said mechanism to return said carriage, a manually operable key, and means serving automatically in response to an operation of said key to shift said element from a certain carriage-return-start-determining position to another carriage-return-start-determining position, said element being engageable by the carriage in either position.

3. In a typing machine having a frame, a carriage thereon, and a carriage returning mechanism; an element shiftable on the frame in the direction, substantially, of carriage movement, said element being engageable by the carriage to cause said mechanism to return said carriage, a manually operable key, means serving automatically in response to an operation of said key to shift said element from a certain carriage-return-start-determining position to another carriage-return-start-determining position, said element being engageable by the carriage in either position, and means acting concomitantly with the return movement of said carriage to restore said element to the first carriage-return-start-determining position.

4. In a typing machine having a frame, a carriage thereon, and a carriage returning mechanism; a body shiftable on the frame in the direction, substantially, of carriage movement, an element carried by said body, said element being displaceable on the body by a tappet on said carriage, means responsive to displacement of said element to cause said mechanism to return said carriage, a manually operable key on the frame, and means serving automatically in response to an operation of said key to shift said body from a certain carriage-return-start-determining position to another carriage-return-start-determining position.

5. In a typing machine having types and a letter-feed carriage cooperative with said types; mechanism for returning the carriage from different line-end positions in respect of a normal-length line and an extended-length line, including a motor mechanism, an element on the carriage, another element engageable by said carriage element, means responsive to engagement of said elements to cause said motor mechanism to return said carriage, a spring tending to shift one of said elements, a latch device restraining said one element in a position determinative of one line end, a key operable to release said one element from said latch for resultant shift of said one element by said spring, and means limiting said shift to a position determinative of the other line end.

6. In a typing machine having types and a letter-feed carriage cooperative with said types; mechanism for returning the carriage from dif-

ferent line-end positions in respect of a normal-length line and an extended-length line, including a motor mechanism, an element on the carriage, another element engageable by said carriage element, means responsive to engagement of said elements to cause said motor mechanism to return said carriage, a spring tending to shift one of said elements, a latch device restraining said one element in a position determinative of one line end, a key operable to release said one element from said latch for resultant shift of said one element by said spring, means limiting said shift to a position determinative of the other line end, and means, acting concomitantly with a return movement of the carriage, to restore automatically said one element to said latch.

7. In a typing machine having a frame and a carriage movable laterally thereon in opposite directions; means for determining two alternative limits of carriage movement in one direction, including, in combination, an element on the frame, an element on the carriage engageable with the frame element substantially to limit the carriage movement in said direction, one of said elements being shiftable, parallelly to the carriage movement, from one position to another position, said positions determining said limits, means tending to shift said element from said one position to the other position, a detent for holding said one element in said one position, means operable to release said detent for resulting shift of said one element to said other position, an abutment separate from the other element and corresponding to said other position to arrest and maintain said shift independently of said detent, said one element being shiftable oppositely for restoration to said detent.

8. In a typing machine having a frame and a carriage movable thereon in advance and return directions; the combination with power-carriage-return mechanism, of an element mounted on the frame for shifts in the direction of carriage movement, said element being engageable by the carriage when the latter comes to a carriage-advance-limiting zone, means responsive to the engagement of said element by the carriage to cause said return mechanism to return said carriage, a normally restrained power device releasable to shift said element from one position to another position in said zone, and means operable at will before the carriage comes to said zone to release said power device for a resulting shift of said element.

9. In a typing machine having a frame and a carriage movable thereon in advance and return directions; the combination with power-carriage-return mechanism, of an element mounted on the frame for shifts in the direction of carriage movement, said element being engageable by the carriage when the latter comes to a carriage-advance-limiting zone, means responsive to the engagement of said element by the carriage to cause said return mechanism to return said carriage, a normally restrained power device releasable to shift said element from one position to another position in said zone, means operable at will before the carriage comes to said zone to release said power device for a resulting shift of said element, and means for restoring said element to said one position by the return movement of the carriage, said restoring means being operative independently of said releasing means.

10. In a typing machine having a frame and a carriage laterally movable thereon in one di-

rection to two alternative positions, a device mounted on the frame for shifts in the direction of carriage movement to define one or the other of said positions, means tending to shift said device to one position, means restraining said device in the other position, a key operable for releasing said device from said restraining means for resulting shift to said one position, and means for restoring said device to said other position and to said restraining means by the carriage movement in the direction opposite to the first-named direction, said restoring means being operative independently of said releasing key.

11. In a typing machine having a frame and a carriage laterally movable thereon in opposite directions, a device adjustable on the frame, parallelly to the carriage movement, to two different positions, said carriage having means engageable with said device in either position substantially to limit the movement of the carriage in one direction, a key, means responding to operation of said key to shift said device in said one direction from one to the other of said positions, and means operative independently of said key and enabling the carriage in its movement opposite to said one direction to restore said device from said other position to said one position.

12. In a margin stop mechanism for a typing machine carriage; a margin stop supported for shifts in the opposite directions of carriage travel, means tending to shift said stop in one of said directions, stop restraining means operable to release said stop for a resultant shift by said shifting means, an abutment for limiting the shift of said stop, a support for said restraining means

and abutment, and means mounting said support for adjustment in said directions for varying the stop-locating positions of said restraining means and abutment.

5 13. In a margin stop mechanism for a typing machine carriage; a margin stop supported for shifts in the opposite directions of carriage travel, means tending to shift said stop in one of said directions, and an arm pivoted to said support and having two abutments spaced apart in the direction of carriage travel, one abutment restraining said stop against movement by said shifting means, said arm being movable about its pivot to retract said one abutment and interpose the other abutment to permit and limit the shift of said margin stop by said shifting means.

10 14. In a margin stop mechanism for a typing machine carriage; a margin stop supported for shifts in the opposite directions of carriage travel, means tending to shift said stop in one of said directions, a support mounted for adjustment in said directions, an arm pivoted to said support and having two abutments spaced apart in the direction of carriage travel, one abutment restraining said stop against movement by said shifting means, said arm being movable about its pivot to retract said one abutment and interpose the other abutment to effect and limit the shift of said margin stop by said shifting means, a key stationary relatively to the adjustment of said support with said arm, and an operating connection from said key to said arm, said connection being flexible to permit adjustment of said arm along with its said support.

HENRY L. PITMAN.

CERTIFICATE OF CORRECTION.

Patent No. 2,244,115.

June 3, 1941.

HENRY L. PITMAN.

It is hereby certified that error appears in the printed specification of the above numbered patent requiring correction as follows: Page 5, second column, line 9, claim 13, after "directions," insert the words and comma --a support mounted for adjustment in said directions,--; and that the said Letters Patent should be read with this correction therein that the same may conform to the record of the case in the Patent Office.

Signed and sealed this 29th day of July, A. D. 1941.

Henry Van Arsdale,
(Seal) Acting Commissioner of Patents.
